UNITED STATES PATENT OFFICE.

OTIS A. MYGATT, OF NEW YORK, N. Y.

DESIGN FOR A REFLECTOR OR SIMILAR ARTICLE.

No. 40,055.

Specification for Design.

Patented June 15, 1909.

Application filed September 18, 1907. Serial No. 393,564. Term of patent 14 years.

To all whom it may concern:

Be it known that I, OTIS A. MYGATT, a citizen of the United States, residing at New York, in the State of New York, have invented a new, original, and ornamental Design for a Reflector or Similar Article, of which the following is a specification, reference being had to the accompanying drawing, forming part thereof.

Figure 1 is a plan of the outer surface of a reflector or similar article embodying the design, and Fig. 2 is a bottom plan showing the appearance of the inner surface of the article.

The polygonal body of the reflector is com-

posed of one piece of transparent glass. The top or outside of the reflector is provided with reflecting prisms extending from about the central opening or collar. The inside of the reflector shows the design in brilliant lines or facets.

I claim:

An ornamental design for a reflector or similar article as shown and described.

OTIS A. MYGATT.
